(57) **CLAIM**

The ornamental design for a keyboard for electronic device, as shown and described.

DESCRIPTION

FIG. 1 is a front perspective view of a keyboard for electronic device, showing our new design; FIG. 2 is a front view thereof; FIG. 3 is a rear view thereof; FIG. 4 is a left-side view thereof; FIG. 5 is a right-side view thereof; FIG. 6 is a top view thereof; FIG. 7 is a bottom view thereof; FIG. 8 is a rear perspective view thereof; and, FIG. 9 is another right-side view thereof as shown in a device environment.

The broken lines illustrating portions of the keyboard for electronic device form no part of the claimed design. The remaining broken lines in FIG. 9 are for environmental purposes only and form no part of the claimed design. The unshaded area surrounding the key array in FIGS. 1 and 2 forms no part of the claimed design.
